UNITED STATES PATENT OFFICE

165,667

AUTOMOBILE SERVING TRAY

Whilman G. Sheets, Bellmead, Tex.

Application September 28, 1951, Serial No. 16,772

Term of patent 7 years

(Cl. D44—10)

To all whom it may concern:

Be it known that I, Whilman G. Sheets, a citizen of United States of America, residing at Bellmead, in the county of McLennan and State of Texas, have invented a new, original, and ornamental Design for an Automobile Serving Tray, of which the following is a specification, reference being had to the accompanying drawing, forming part thereof.

In the drawing

Fig. I is a perspective view of an automobile serving tray showing my new design;

Fig. II is a top plan view of the automobile serving tray showing the hooks in retracted position.

Fig. III is a bottom plan view of the automobile serving tray showing the legs in retracted position.

I claim:

The ornamental design for an automobile serving tray, substantially as shown and described.

WHILMAN G. SHEETS.
